APPARATUS FOR ELIMINATING DESTRUCTIVE, SELF-EXCITED VIBRATIONS IN STEAM GENERATORS

Leo J. J. Cohan, Simsbury, and William J. Deane, Hartford, Conn., assignors to Combustion Engineering, Inc., Windsor, Conn., a corporation of Delaware

Filed June 17, 1964, Ser. No. 375,713

8 Claims. (Cl. 122—4)

This invention relates to apparatus for eliminating self-excited vibration problems created by gases flowing through a duct, and over tubular members positioned within the duct and extending in a direction transversely of the gas flow path, and in particular to apparatus for eliminating such self-excited vibration problems existing in the rear gas pass of a steam generator.

In recent years, steam generators are becoming increasingly larger. As the size of these units have increased, the problem of self-excited vibrations has become more prevalent. The vibrations are caused by the combustion gases in flowing over tubular panels positioned in the rear gas pass of the steam generator. Whenever standing wave forms are created in the duct or chamber which are in resonance or harmony with the exciting frequency, vibrations are created which can lead to the ultimate failure of equipment, and also creates noise which is highly disturbing to operating personnel.

To overcome this problem, baffles have been positioned within the rear gas pass of units where vibrations exist. These baffles break up the standing wave forms, thus eliminating or substantially reducing the vibrations. However, in the past there have been no means by which it can be forecast which units, when constructed, will encounter these problems, or if they are encountered, just where the baffles should be located to most economically and efficiently eliminate the problem. Thus it is necessary to stop operation of the unit at least once, or in some instances a number of times, to install the baffles in the gas pass. This can be extremely expensive and troublesome to utility companies where the steam generator is being used in conjunction with a turbine for generating electricity.

It is the object of our invention to provide for a systematic manner of determining where and how many baffles should be positioned within a gas pass of a steam generator to economically and efficiently eliminate self-excited resonant vibrations therefrom.

The invention will be more readily understood from the following description taken in conjunction with the accompanying drawings wherein:

FIG. 1 is a diagrammatic representation of a vertical section of a steam generator;

FIG. 2 is an enlarged sectional view of a portion of the rear gas pass of a steam generator, taken on line 2—2 of FIG. 1;

FIG. 3 is an illustration of typical gas pulsations existing in the gass pass of a steam generator;

FIG. 4 is an illustration of various standing wave forms which may exist in a duct;

FIG. 5 is a graph showing what standing wave forms which may exist in a gas pass of a steam generator based on the width of the gas pass and the frequency of the vibrations; and,

FIG. 6 is a chart which illustrates the number and location of baffles determined in accordance with our invention in order to preclude the presence of damaging self-excited vibrations therefrom.

Looking now to FIG. 1, the steam generator illustrated contains a furnace 20, the walls of which are lined with steam generating tubes 22. Burners 24 supply the furnace

2

with fuel and air which is burned therein. The hot combustion gases travel upwardly through the furnace and out through the horizontal gas pass 26, then continue downwardly through vertical gas pass 28 before being exhausted.

The combustion gases give up heat to the heat exchange surfaces contained within the boiler, thus creating superheated steam to be used in driving a turbine for generating electricity. Water enters economizer 30 and is heated to some extent before flowing to the steam and water drum 32. Water flows from drum 32 downwardly to inlet header 34, which distributes the water to the tubes 22. A steam and water mixture leaves tubes 22, flowing into outlet header 36, from where it is conveyed back to drum 32. The steam separates out in drum 32, flowing through lines 38 to the primary superheater sections 39, 40 and 41 which are in series flow relationship. Superheated steam leaving section 41 flows by way of pipe 42 to secondary superheater section 44. The steam is superheated to a greater extent in flowing through secondary superheaters 44, 46 and 48. The superheated steam flows from section 48 to its ultimate point of use, for example a steam turbine used to generate electricity.

It is in the rear gas pass 28 where the primary superheater sections 39, 40 and 41 are located where vibration problems are usually encountered, and in accordance with our invention baffles 50 are positioned in this area, thus forming a plurality of parallel passageways through which the combustion gases pass.

When a gas flows transversely over a tube, the wake behind the tube is no longer regular or streamlined, but exhibits distinct clockwise and counterclockwise vortices in a regular, periodic manner, as illustrated in FIG. 3. This shedding, from alternate sides of the tubes, causes a varying force on the tubes perpendicular to the normal flow of the gas. When the vortex shedding frequency coincides with the natural frequency of the gas column, vibration occurs. This is synonymous to motivating a large pendulum with a small force applied with a hammer at the natural frequency of the pendulum. If this small force is applied during each cycle, the amplitude will continually increase. This is a condition of resonance between the exciting force and the natural harmonic motion of the pendulum. In a gas pass containing tubes therein, the vortices are the hammer, and the gas stream is the pendulum.

In any duct containing tubular objects where a gas is passing therethrough, if the exciting frequency is in resonance with the frequency of the chamber or duct, standing wave forms are created. Whether or not the existing frequency is in resonance with the frequency of the chamber or duct is dependent on such factors as gas velocity, pressure, temperature, size and vertical and horizontal spacing of the tubular objects, width of the duct or chamber, and others.

FIG. 4 depicts some typical wave formations which may exist in a duct. As can be seen, a one-half wave, or first harmonic, would extend across the entire width of the duct. Likewise, a full wave, or second harmonic, extends across 50 percent of the duct width; a 1½, or third harmonic, would extend across 33½ percent of the duct width, etc. The nodes are the intersection points of the loops of the wave formations, and to eliminate any standing wave formations from a duct, the waves should be broken or interrupted at a point between two nodes, preferably, although not necessarily, at their midpoint. Thus one manner of deresonating a resonant duct or chamber is to subdivide that chamber by placing baffles therein, thus forming a plurality of chambers which would have a frequency that differed from, and was no integral sub-multiple of, the exciting frequency.

From calculated performance conditions, the graph shown in FIG. 5 was plotted of the resonant frequency of a duct and the vortex shedding frequency (based on a gas temperature of 1460° F. absolute). By taking measurements in steam generating units in existence, it was determined that the natural frequency in the rear gas pass of most units was in the range of 40-100 cycles per second (c.p.s.). By checking the graph of FIG. 5, the harmonic that might exist in any unit of a given width can be fairly accurately determined. It was also found that vibration trouble rarely occurred in units where the rear gas was less than 22 feet in width.

From FIG. 4 it can be seen that a baffle placed anywhere would theoretically eliminate a standing first harmonic or one-half wave, with the midpoint, or dead center, being the optimum location. The midpoint, however, would be the worst possible location to deresonate a second harmonic, or full wave, since there is a displacement node at the center. Thus a baffle placed here would be useless, since the wave could travel through it; or a first harmonic or one-half wave would exist on each side. The optimum baffle location for a full wave would be the one-quarter point, furthest from any of the nodes. But both one-quarter points should not be baffled, because this could produce a one-half wave in the middle. Thus it can be seen that to develop a fixed formula for baffle placement which can be applied to any boiler before it is constructed (and thus before it is known what harmonics might exist in the rear gas pass) presents difficulties.

Based on the measurements taken of steam generating units in existence, a systematic manner was derived for determining the most economic and efficient number and position of baffles to be placed in the rear gas pass to eliminate vibration problems. Our formula is applicable for all units whose rear gas pass width falls within the range of 22-87 feet. Above 22 feet, the primary concern is the full wave, so a baffle is placed at the one-quarter point. The one-quarter point will also eliminate a one-half and 1½ standing wave (see FIG. 4).

This single baffle placement is adequate until the larger of the two cavities approaches 22 feet, or $\frac{3}{4}W=22$ feet, where W is the width of the gas pass. Thus when W , the width of a unit, is greater than 29 feet, more than one baffle is needed. If we quarter point the larger cavity with a second baffle, there will then be three cavities formed in the following proportion:

$$\frac{1}{4}W : \frac{1}{4}(\frac{3}{4})W : (\frac{3}{4})(\frac{3}{4})W ; \text{ or } 25\%W : 18.75\%W : 56.25\%W .$$

Again the largest of the three cavities may grow until $56.25\%W=22$ feet; or until the width of a unit is 39 feet. Thus on units whose gas pass width is greater than 39 feet, three baffles would be positioned, forming four cavities as follows:

$$\frac{1}{4}W : \frac{1}{4}(\frac{3}{4})W : \frac{1}{4}(\frac{3}{4})^2W : (\frac{3}{4})^3W ; \text{ or } 25\%W : 18.75\%W : 14.06\%W : 42.19\%W .$$

Thus it can be seen that the number and position of baffles are determined so as to leave cavities in accordance with the following:

$$\frac{1}{4}W : \frac{1}{4}(\frac{3}{4})^1W : \frac{1}{4}(\frac{3}{4})^2W : \dots$$

$\dots : \frac{1}{4}(\frac{3}{4})^{n-1}W : (\frac{3}{4})^nW$, wherein W is the total width of the gas pass, and n is the number of baffles. When the last cavity in the series, or $(\frac{3}{4})^nW$ reaches 22 feet, another baffle is needed.

This manner of determining the number and position of baffles can be used on units having a width up to as large as 87 feet. Above 87 feet, the first cavity, or $\frac{1}{4}W$,

would be 22 feet or greater, and this would be undesirable. Thus our means of determining the placement of baffles should not be applied to steam generating units which have a rear gas pass in excess of 87 feet.

FIG. 6 is a chart showing the number and location of baffles that should be placed in accordance with our invention to overcome vibration problems, for units having a gas pass width falling within the range of 22-87 feet.

The baffle placement series developed provides cavities that are always in a 4 to 3 width ratio from the left side, except the last two cavities which are in a 3 to 1 width ratio. This can be seen in FIG. 6. The only way that the far right baffle could be at a nodal point would be if there were two waves, which ran through the baffle. This would mean three loops on one side of the baffle and one loop on the other side. Since there will be no cavities over 22 feet wide in accordance with our invention, 1½ waves would be required to exist at a frequency well in excess of 100 c.p.s. (see FIG. 5). Although this condition is possible, it is highly improbable based on a study of units in existence, where the frequency of most units fell within the range of 40-100 c.p.s.

FIG. 2 shows the baffle placement in the rear gas pass of a unit in accordance with the FIG. 6 chart, of a unit the gas pass width of which falls within the range of 69-87 feet. As shown, the baffles 50 are secured in position by rods 52 welded to tubes 40 of the superheater, although any suitable manner of securely positioning and supporting the baffles can be used. The baffles should be made of a suitable metal capable of withstanding the temperatures of the combustion gases (800-1500° F.).

Although the invention has been illustrated in connection with primary superheater surfaces, if vibration problems are encountered in the secondary superheater, re-heater, or economizer areas, baffles could be placed in these areas also in accordance with our invention. Most of the vibration problems which have occurred in the past have been in the primary or low temperature superheater area. It has also been found that most vibration problems occur on oil or gas fired steam generators.

As illustrated in FIG. 2, the baffles are of a height so as to extend from the top of the tubular panels 41 to the bottom of the tubular panels 39. It may be possible to eliminate vibration problems by using three smaller baffles, vertically spaced, in place of each baffle shown in FIG. 2. Each of these three baffles would extend from the top of one panel to a point just slightly below the bottom of the panel.

The figure 22 feet has more or less been arbitrarily chosen as a starting point for developing the baffle placement formula, based on past experience. It could be possible to start with a figure within the range of 20-25 feet, for example, and still apply the formula with considerable success in preventing vibration problems.

What we claim is:

1. In combination, a furnace wherein hot combustion gases are generated by the burning of fuel therein, a vertical gas pass having front, rear and side walls connected to the furnace through which the combustion gases flow, a plurality of tube panels positioned within the gase pass, each tube panel being made up of a plurality of parallel vertically spaced horizontal tube portions which extend in a direction running from the front to the rear wall, and vertical baffle means positioned within the gas pass which are parallel to the tube panels, the number and position of the baffle means being determined substantially in accordance with the following:

Total duct width, ft.	Number of baffles	(Side 1)			(Side 2)		
		Baffle location in terms of percent of total duct width					
22 to 29	1	25	100		75	56.25	
29 to 39	2	25	18.75	14.06	14.06	42.19	
39 to 52	3	25	18.75	14.06	10.55	31.64	
52 to 69	4	25	18.75	14.06	10.55	7.91	23.73
69 to 87	5	25	18.75	14.06			

to thereby preclude the presence of damaging self-excited vibrations caused by the combustion gases flowing past the tube panels.

2. In combination, a furnace wherein hot combustion gases are generated by the burning of fuel therein, a vertical gas pass having front, rear and side walls connected to the furnace through which the combustion gases flow, a plurality of tube panels positioned within the gas pass, each tube panel being made up of a plurality of parallel, vertically spaced horizontal tube portions which extend in a direction running from the front to the rear wall, and vertical baffle means positioned within the gas pass which are parallel to the tube panels, the number and position of the baffle means being such that a plurality of parallel passageways result, the relationship of the successive widths of the passageways defined by the following:

$$\frac{1}{4}W : \frac{1}{4}(\frac{3}{4})^1W : \frac{1}{4}(\frac{3}{4})^2W : \dots : \frac{1}{4}(\frac{3}{4})^{n-1}W : (\frac{3}{4})^nW$$

wherein W is the total width of the gas pass and W is within the range of 22-87 feet, n is the number of baffle means to thereby preclude the presence of damaging self-excited vibrations caused by the combustion gases flowing past the tube panels and $(\frac{3}{4})^nW$, the largest passageway, approaches or equals 22 feet but does not exceed 22 feet.

3. In combination, a furnace wherein hot combustion gases are generated by the burning of fuel therein, a vertical gas pass having four enclosing walls connected to the furnace through which the combustion gases flow, a plurality of tube panels positioned within the gas pass, each tube panel containing a plurality of parallel, vertically spaced horizontal tube portions which extend in a direction parallel to two of the enclosing walls of the gas pass, and vertical baffle means positioned within the gas pass which are parallel to the tube panels, the number and position of the baffle means being such that a plurality of parallel passageways result, the relationship of the successive widths and number of the passageways defined by the following:

$$\frac{1}{4}W : \frac{1}{4}(\frac{3}{4})^1W : \frac{1}{4}(\frac{3}{4})^2W : \dots : \frac{1}{4}(\frac{3}{4})^{n-1}W : (\frac{3}{4})^nW$$

wherein W is the total width of the gas pass and W is within the range of 22-87 feet, n is the number of baffle means, and $(\frac{3}{4})^nW \leq 22$ feet, $(\frac{3}{4})^nW$ being the largest passageway, to thereby preclude the presence of damaging self-excited vibrations caused by the combustion gases flowing past the tube panels.

4. In combination, a furnace wherein hot combustion gases are generated by the burning of fuel therein, a vertical gas pass means having four enclosing walls connected to the furnace through which the combustion gases flow, a plurality of tube panels positioned within the gas pass means, each tube panel containing a plurality of parallel, vertically spaced horizontal tube portions which extend in a direction parallel to two of the enclosing walls of the gas pass, and a vertical baffle means positioned within the gas pass which is parallel to the tube panels, said two of the enclosing walls of the gas pass being at least 22 feet but less than 29 feet apart, with the baffle means being positioned approximately 25 percent of the total width distance from one of said enclosing walls, to thereby preclude the presence of damaging self-excited vibrations caused by the combustion gases flowing past the tube panels.

5. In combination, a furnace wherein hot combustion gases are generated by the burning of fuel therein, a vertical gas pass means having four enclosing walls connected to the furnace through which the combustion gases flow, a plurality of tube panels positioned within the gas pass means, each tube panel containing a plurality of parallel, vertically spaced horizontal tube portions which extend in a direction parallel to two of the enclos-

ing walls of the gas pass, and two vertical baffle means positioned within the gas pass which are parallel to the tube panels, said two of the enclosing walls of the gas pass being at least 29 feet but less than 39 feet apart, with the two baffle means being positioned approximately 25 percent and 43.75 percent of the total width distance from one of said enclosing walls, respectively, to thereby preclude the presence of damaging self-excited vibrations caused by the combustion gases flowing past the tube panels.

6. In combination, a furnace wherein hot combustion gases are generated by the burning of fuel therein, a vertical gas pass means having four enclosing walls connected to the furnace through which the combustion gases flow, a plurality of tube panels positioned within the gas pass means, each tube panel containing a plurality of parallel, vertically spaced horizontal tube portions which extend in a direction parallel to two of the enclosing walls of the gas pass, and three vertical baffle means positioned within the gas pass which are parallel to the tube panels, said two of the enclosing walls of the gas pass being at least 39 feet but less than 52 feet apart, with the three baffle means being positioned approximately 25 percent, 43.75 percent, and 57.81 percent of the total width distance from one of said enclosing walls, respectively, to thereby preclude the presence of damaging self-excited vibrations caused by the combustion gases flowing past the tube panels.

7. In combination, a furnace wherein hot combustion gases are generated by the burning of fuel therein, a vertical gas pass means having four enclosing walls connected to the furnace through which the combustion gases flow, a plurality of tube panels positioned within the gas pass means, each tube panel containing a plurality of parallel, vertically spaced horizontal tube portions which extend in a direction parallel to two of the enclosing walls of the gas pass, and four vertical baffle means positioned within the gas pass which are parallel to the tube panels, said two of the enclosing walls of the gas pass being at least 52 feet but less than 69 feet apart, with the four baffle means being positioned approximately 25 percent, 43.75 percent, 57.81 percent, and 68.36 percent of the total width distance from one of said enclosing walls, respectively, to thereby preclude the presence of damaging self-excited vibrations caused by the combustion gases flowing past the tube panels.

8. In combination, a furnace wherein hot combustion gases are generated by the burning of fuel therein, a vertical gas pass means having four enclosing walls connected to the furnace through which the combustion gases flow, a plurality of tube panels positioned within the gas pass means, each tube panel containing a plurality of parallel, vertically spaced horizontal tube portions which extend in a direction parallel to two of the enclosing walls of the gas pass, and five vertical baffle means positioned within the gas pass which are parallel to the tube panels, said two of the enclosing walls of the gas pass being at least 69 feet but less than 87 feet apart, with the five baffle means being positioned approximately 25 percent, 43.75 percent, 57.81 percent, 68.36 percent, and 76.27 percent of the total width distance from one of said enclosing walls, respectively, to thereby preclude the presence of damaging self-excited vibrations caused by the combustion gases flowing past the tube panels.
